DESIGN FOR A SERVICE STAND FOR THE DISPLAY OF HORS D'OEUVRES

Louis Kessler, New York, N. Y.

Application February 1, 1935, Serial No. 55,187

Term of patent 3½ years

To all whom it may concern:

Be it known that I, Louis Kessler, a citizen of the United States of America, residing in Manhattan, county of New York, and State of New York, have invented a new, original, and ornamental Design for a Service Stand for the Display of Hors d'Oeuvres, of which the following is a specification, reference being had to the accompanying drawing, forming part thereof, wherein,

The figure is a perspective view of a service stand for the display of hors d'oeuvres, showing my new design.

I claim:

The ornamental design for a service stand for the display of hors d'oeuvres, substantially as shown.

LOUIS KESSLER.
